ELECTRIC FLAT IRON GUARD, FOR ATTACH-MENT TO AN IRONING BOARD

Margaret Stuart, 6148 Smith Road, Brook Park, Ohio

Filed Sept. 18, 1963, Ser. No. 76,630

Term of patent 7 years

(Cl. D49—6)

FIG. 1

I claim:

The ornamental design for an electric flat iron guard, for attachment to an ironing board, as shown and described.
